DESIGN FOR A BRASSIÈRE OR THE LIKE

William Rosenthal, New York, and Charles M. Sachs, Brooklyn, N. Y., assignors to Maiden Form Brassière Company, Inc., New York, N. Y., a corporation of New York

Application January 23, 1940, Serial No. 89,650

Term of patent 14 years

To all whom it may concern:

Be it known that we, William Rosenthal, a citizen of the United States and residing at No. 115 Central Park West, in the Borough of Manhattan, city, county, and State of New York, and Charles M. Sachs, a citizen of the United States and residing at No. 1753 47th Street, Borough of Brooklyn, county of Kings, city and State of New York, have invented a new, original, and ornamental Design for a Brassière or the Like, of which the following is a specification, reference being had to the accompanying drawing, forming part thereof.

Referring to the drawing:

Fig. 1 is a front perspective view of a brassière showing our new design; and

Fig. 2 is a rear perspective view of the brassière shown in Fig. 1.

The characteristic feature of our design, which resides in the center front of the disclosed brassière having a diaphragm band, is the specific contrasting insert consisting of an upper portion which comprises a center front part of the pockets and a lower portion which comprises a center front part of the diaphragm band, all as shown.

We claim:

The ornamental design for a brassière or the like, substantially as shown and described.

WILLIAM ROSENTHAL.
CHARLES M. SACHS.
